UNITED STATES PATENT OFFICE

151,729

DESIGN FOR A CONTAINER FOR A PERFUME BOTTLE OR THE LIKE

Georges Baud, Paris, France

Application March 29, 1946, Serial No. 128,049
In France February 7, 1946

Term of patent 14 years

(Cl. D58—11)

To all whom it may concern:

Be it known that I, Georges Baud, a citizen of France, residing in Paris, France, have invented a new, original, and ornamental Design for a Container for a Perfume Bottle or the like, of which the following is a specification, reference being had to the accompanying drawing, forming part thereof.

Fig. 1 is a front view of a container in closed position, showing my new design;

Fig. 2 is a front view of the container in open position; and

Fig. 3 is a back view of the container in closed position.

I claim:

The ornamental design for a container for a perfume bottle or the like, as shown.

G. BAUD.
